COAT COLLAR CONSTRUCTION

Marcus Breier, Amsterdam, N. Y., assignor to
 Marcus Breier Sons, Inc., Amsterdam, N. Y., a
 corporation of New York

Application July 8, 1949, Serial No. 103,670

6 Claims. (Cl. 2-98)

1

This invention relates to a garment such as a jacket having a collar facing of alpaca, mouton, fur or the like including a protective covering or envelope for the facing and more particularly to a garment having a water repellent covering formed as a portion of the collar construction which serves to enclose the facing during inclement weather to protect the same against snow or rain and which may be turned beneath the collar substantially concealed from view during clement weather.

The chief object of the present invention is to provide a garment having a collar facing of alpaca, mouton, fur or the like provided with a protective covering or envelope for the facing to protect the same during inclement weather.

An object of the invention is to provide a garment having a collar facing of alpaca, mouton, fur or the like having a water repellent covering capable of enclosing the facing during inclement weather and which may be turned under the collar when desired to serve in effect as an under collar.

A further object is to provide a collar construction including a facing, a lining and a protective covering for the facing placed adjacent the lining and secured to three sides of the facing and lining, the remaining side hanging free whereby the covering may be turned over the facing when desired to protect the same against rain or snow. Other objects of my invention will be readily perceived from the following description.

This invention relates to a garment including a neck opening and having a collar extending about the opening and secured to the body of the garment. A protective covering is secured to the collar and extends free over the rear of the collar. Such covering is of a length such that it may be turned over the facing of the collar to protect the same against rain or snow while during clement weather it may be placed under the collar adjacent the lining to substantially conceal the covering from view.

The attached drawing illustrates a preferred embodiment of my invention, in which

Figure 1 is a view in elevation of a garment such as a jacket embodying the present invention;

Figure 2 is a view in elevation illustrating the water repellent covering in position protecting the facing of the collar;

Figure 3 is a sectional view of the collar construction;

Figure 4 is a sectional view of the collar construction having the water repellent covering in place protecting the facing; and

2

Figure 5 is a sectional view through a corner of the collar construction.

Referring to the attached drawing, there is shown a garment such as a jacket or the like including a body portion 2 formed in the usual manner and including an exterior wear and decorative covering 3 and a lining 4. The garment is provided with the usual neck opening 5 around which a collar 6 extends. The collar 6 includes a facing 7 of alpaca, mouton, fur or the like and a rear lining 8. Facing materials of the type contemplated possess undesirable properties when wet from rain or snow and do not afford desired protection under such conditions. To eliminate these disadvantages, I provide a protective covering or envelope 9 for the facing 7 formed as a part of the collar construction. Preferably, covering 9 is water repellent or water resistant to protect the facing against moisture.

Considering Figure 3, it will be observed covering 3 and lining 4 are turned over at their edges 10 and 11, the collar elements 7 and 8 fitting therebetween. Stitching 10 holds these elements together. The opposite ends 11' and 12 of the collar facing 7 and collar lining 8 are turned over and the edge 13 of covering 9 placed therebetween, these elements being held together by stitching 14. The opposite end of the envelope 9 is turned over as shown at 15 to form a reinforcement. Button holes 16 are formed in the envelope 9 adapted to cooperate with buttons 17 on the lining 4 adjacent the opening 5 to hold the envelope in place over the facing of the collar.

In Figure 4, I have illustrated covering 9 turned over the facing 7 and secured in place thereover to protect the facing against rain or snow during inclement weather.

Figure 5 illustrates a section of the collar construction looking toward the tip of the collar. The manner in which the covering is tucked in between the collar facing and collar lining at the tips of the collar is shown.

During pleasant weather, the covering 9 is placed beneath the collar 6 and forms in effect an under collar. The covering 9 is substantially concealed from observation and does not detract from the appearance of the garment. During inclement weather, the collar may be turned up and covering 9 turned thereabout enclosing the facing 7 and being fastened in place by co-operating elements 15 and 16 to protect the facing against rain or snow. Generally, the water repellent covering may be made of the same material or a material similar in appearance to the exterior of the garment. If desired, snap fasteners

may be secured to the collar lining and to the covering; when the covering is turned back on the collar to expose the facing, the covering may be attached by the fasteners so that it becomes part of the under collar when not in use.

It will be appreciated if desired the lining 8 of the collar and the covering 9 may be combined and formed from a single piece of cloth folded over to provide an extended portion capable of being placed over the facing. Such construction of course is not as desirable as the preferred embodiment since it may be somewhat more expensive.

The present invention provides simple and ready means of protecting a collar facing of fur, alpaca, mouton and like materials during inclement weather while permitting the garment to present an attractive appearance. The protective covering provided does not detract from the appearance of the garment during normal use and permits all the advantages of pile and fur collars to be retained. The protective water repellent covering provided is not expensive and affords adequate protection for the more expensive facing material against rain or snow.

While I have described a preferred embodiment of my invention it will be understood my invention is not limited thereto since it may be otherwise embodied within the scope of the following claims.

I claim:

1. In a garment of the character described, the combination of a body including an exterior covering and an interior lining and having a neck opening, a collar member extending about the opening attached to the body including a facing and a rear lining attached to each other and to the body, and a water repellent covering for the collar, said water repellent covering having an end thereof fitted between and attached to the outer ends of the facing and lining, the other end of the covering folding beneath the collar adjacent the rear lining and being adapted to be turned over the facing to enclose the same.

2. A garment according to claim 1 character-

ized by the fact that the water repellent covering is attached to the collar at its outer edge and its side edges, the covering extending free adjacent the remaining edge of the collar.

3. A garment according to claim 2 characterized by the fact that means are provided to fasten the covering in place enclosing the facing.

4. A garment according to claim 3 characterized by the fact that the free edge of the covering is reenforced to assure that it lies flat against the neck of a wearer.

5. In a garment of the character described, the combination of a body including an exterior covering and an interior lining and having a neck opening, a collar member extending about the opening attached to the body and including a facing and a rear lining, ends of said facing and said lining extending between the exterior covering and interior lining and being attached thereto, a water repellent covering for the collar, an end of the water repellent covering extending between the opposite ends of the facing and lining and being attached thereto, the covering being secured on three sides between the lining and facing with a fourth side thereof extending free adjacent the rear lining, said covering being adapted to be turned over the facing to protect the same during inclement weather.

6. A garment according to claim 5 characterized by the fact that fastening members are placed on the interior lining adjacent the neck opening and cooperating means are provided in the water repellent covering to hold the covering in place enclosing the collar facing.

MARCUS BREIER.
